UNITED STATES PATENT OFFICE.

CHARLES LESLIE BAKER, OF ST. JOSEPH, MISSOURI.

STEAM-REGULATED EXHAUST NOZZLE.

Application filed February 10, 1921. Serial No. 443,974.

To all whom it may concern:

Be it known that I, CHARLES L. BAKER, a citizen of the United States, residing at St. Joseph, in the county of Buchanan, State of Missouri, have invented certain new and useful Improvements in Steam-Regulated Exhaust Nozzles; and I do hereby declare the following to be a full, clear, and exact description of the invention, such as will enable others skilled in the art to which it appertains to make and use the same.

This invention relates to new and useful improvements in exhaust nozzle regulating mechanisms, and particularly to an improvement over the prior patent issued to myself October 22, 1912, and numbered 1,042,070.

The particular improvement consists in providing a steam motor for opening and closing the gates or valves at the tip of the exhaust nozzle of a railway locomotive.

One object of the invention is to provide a means for automatically moving the gates or valves into open or closed position which is controllable from the cab of the locomotive, by the engineer.

Another object is to provide a motor of this character which is actuated forwardly by steam pressure and restored to normal position by spring pressure.

Other objects and advantages will be apparent from the following description when taken in connection with the accompanying drawings.

35 In the drawings:

Figure 1 is a top plan view of the exhaust nozzle and operating means, the locomotive being shown in section.

Figure 2 is an enlarged vertical longitudinal sectional view through the steam motor which actuates the gates or valves of the nozzle.

Figure 3 is a vertical transverse sectional view through the gear end portion of the casing of the motor, on the line 3—3 of Figure 2.

Figure 4 is a vertical transverse sectional view through the motor casing, on the line 4—4 of Figure 2, showing the door through which access is obtained to the interior of the casing.

Figure 5 is a vertical transverse sectional view through the casing, on the line 5—5 of Figure 2, showing the guide for the rack bar.

Referring particularly to the accompany-

ing drawings, 10 represents the shell of the smoke box of the locomotive, 11 the exhaust nozzle, and 12 the gates or valves mounted on the tip of the nozzle and actuated into open or closed position by means of the oppositely threaded shaft 13 which engages the bifurcated projections 14 of the gates.

On the outside of the shell 10 an elongated casing 15 is secured by means of the bolts 16, said casing having a removable cover 17, secured to the casing by means of the bolts 18. The forward end of the casing 15 is slightly enlarged at its lower portion, and extending transversely through the center 70 of this portion of the casing is a shaft 19, on which are keyed the gears 20 and 21, the former being larger in diameter than the latter. Also extending through this portion of the casing, and below the shaft 19, is a 75 shaft 22 on which is keyed a gear 23 which meshes with the gear 20, said shaft extending through the inner side wall of the casing and through the bushing 24, which is secured within an opening in the wall or 80 shell 10, and into the smoke box. The inner end of the shaft 22 is connected with the adjacent end of the threaded shaft 13 by means of the coupling 25. Mounted within the casing 15, above and parallel with the 85 shaft 19, is a stub shaft 26 on which is rotatably supported a roller 27. Depending from the top wall of the casing is a web 28 and formed in one side of this web is a transverse groove 29 in which is slidably 90 disposed a rack bar 30, said rack bar extending longitudinally within the casing and engaging with the gear 21, with its back or upper edge held in alignment against the roller 27, and between the flanges 95 27' on the roller.

The other end wall of the casing is formed with a central opening 31, through which the reduced and cylindrical portion 32 of the rack bar 30 is slidably disposed. The cylindrical portion of the rack bar, within the casing is threaded to receive thereon the nuts 33 and 34, the latter of which has a reduced extension 34' which is received in the adjacent end of the coil 100 spring 35 which is disposed in encircling relation to the rack bar, and bears with its other end against the rack bar guide 28. In this portion of the casing there is formed an access opening 36, which is covered by a 110 hinged door 37, the same being retained in closed position by the latch 38. A removable

plate 39 is secured on the web 28, to retain the rack bar in the groove thereof.

Bolted to the apertured end of the casing 15 is a cylinder 40 in which the adjacent 5 end of the rack bar 30 moves, and has attached thereto a piston 41. A steam pipe 42 is secured in the head of the cylinder to admit steam to the cylinder against the piston, as will be readily understood. This 10 cylinder 40 is covered with asbestos, as shown at 43. In the pipe 42 is disposed a two way coupling 44, the branch 44' leading to a lubricator valve, not shown, while the branch 44'' leads to a drain valve not 15 shown. The pipe 42 leads to a globe valve located in the cab of the locomotive, but not shown by means of which steam is admitted to the pipe to be conveyed to the cylinder and against the piston to drive the 20 piston toward the other end of the cylinder, and thereby cause the rack bar to rotate the shaft 19, by its engagement with the gear 21, and by this rotation of the shaft 19, the gear 20 will cause the shaft 22 to rotate, by 25 the meshing of the gear 21 with the gear 23. The rotation of the shaft 22, through the coupling 25, causes the rotation of the threaded shaft 13, and the swinging of the gates 12 into closed or partially closed 30 position. When the steam pressure is reduced or cut off from the cylinder 40 the spring, which was compressed under the previously mentioned movement of the piston, is permitted to again expand to normal position, 35 and rotate the shafts and gears so as to move the gates toward open position. When the steam pressure is high the piston will be moved forwardly to swing the gates toward closed position, and thereby reduce 40 the size of the opening at the tip of the exhaust nozzle, and when the pressure is reduced, the spring exerts pressure to move the piston back and thereby rotate the shaft 13 to swing the gates toward open position.

When it is desired to change the tension 45 of the spring 35, the door 37 is swung into open position, and by reaching through the opening 36, the nuts 33 and 34 can be turned.

By removing the cover 17, access to all 50 of the mechanism, within the casing be readily had for adjustments or repairs.

What is claimed is:

1. An actuating mechanism for the draft control of a steam boiler furnace comprising a casing, a depending web in one end of 55 said casing, said web being formed with a transverse groove, a rack bar slidable through said groove, a guide roller positioned above the rack bar and contacting therewith, and a rack bar retaining plate 60 secured to the said web and spanning said groove.

2. An actuating mechanism for the draft control of a steam boiler furnace comprising a casing having an enlarged forward end portion, a depending web formed in the enlarged portion of the casing, said web being provided with a transverse groove, a rack bar slidable through said groove, a rack 65 bar retaining plate secured to the said web and spanning said groove, and a door formed in the smaller end portion of the casing.

3. An actuating mechanism for the draft control of a steam boiler furnace comprising a casing, a depending web formed in 75 the forward end of the casing, said web being provided with a transverse groove, a rack bar slidable through the groove, means cooperating with the bar for operating the shutters of a draft control, a rack bar retaining plate secured to the said web and spanning 80 said groove, and a door for said casing.

In testimony whereof, I affix my signature, in the presence of two witnesses.

CHARLES LESLIE BAKER.
